COUCH WITH SWINGABLY MOUNTED BACK
REST OR PILLOW SUPPORT

James Filiero, Astoria, N. Y., assignor to The
Englander Company, Inc., Chicago, Ill., a cor-
poration of Delaware

Application October 6, 1950, Serial No. 188,678

2 Claims. (Cl. 5—59)

1

This invention relates to couches and has par-
ticular reference to a back rest or pillow support
therefor which is swingable to an out-of-the-way
position so as to permit the couch being used as
a bed.

An object of the invention is to provide a couch
with a back rest or pillow support which extends
longitudinally of one side thereof to provide a
support for the back when the couch is used as a
seat and which is swingable to a position at one
side of the couch when the same is to be used as
a bed.

Couches of the studio type are made of suffi-
cient width to provide a comfortable bed but such
couches do not provide a comfortable seat for the
reason that the same are too wide and usually
require pillows and the like being supported
against a wall of the room in order to take up the
excess width of the couch and provide a sup-
port for the back. The present construction pro-
vides a back rest which is upholstered or which
may have pillows positioned thereagainst to re-
duce the width of the couch so that a person may
be seated thereon with the upholstered back rest
or pillows providing a back support and with the
feet of the person resting upon the floor.

Still another object of the invention is to pro-
vide a back rest of said character which is
mounted for rocking movement so that a person
seated on the couch may adjust the back rest to
the desired angularity by engagement of his back
thereagainst.

With the foregoing and other objects in view,
reference is now made to the following specifica-
tion and accompanying drawings in which the
preferred embodiments of the invention are illus-
trated.

In the drawings:

Fig. 1 is a perspective view of a couch provided
with a back rest or pillow support constructed in
accordance with the invention.

Fig. 2 is an end view thereof.

Fig. 3 is an end view showing the couch disposed
in bed forming relation and the back rest or pil-
low support moved to an out-of-the-way position.

Fig. 4 is an enlarged fragmentary side view of
the back rest or pillow support.

Fig. 5 is a front view thereof with the back
panel shown in dotted outline.

Fig. 6 is a sectional view taken approximately
on line 6—6 of Fig. 5.

Fig. 7 is an enlarged view showing the back rest
or pillow support moved to an out-of-the-way
position.

Fig. 8 is an end view of a modified form of back

rest which permits of adjusting the angularity
thereof.

Fig. 9 is an end view showing the couch moved
to bed forming relation and the back rest moved
to the out-of-the-way position.

Fig. 10 is an enlarged fragmentary view of the
back rest.

Fig. 11 is a fragmentary vertical sectional view
taken approximately on line 11—11 of Fig. 7.

Referring to the drawings by characters of ref-
erence, and more particularly to the form of the
invention illustrated in Figs. 1 to 7 inclusive of
the drawings, the back rest or pillow support in-
cludes a panel 10 extending longitudinally of a couch 11 and which is affixed thereto so as to
provide a support for the back of an individual
when seated on the couch, or a support against
which pillows 12 may be disposed in angular rela-
tion thereagainst.

The panel 10 is mounted on vertical posts 13
located adjacent the ends of the couch which
posts are secured thereto by rivets 14 or equivalent
fastening means with the upper ends of the posts
projecting above the couch and connected with
the panel 10 by pairs of flat link members 15 and
16. Each pair of link members 15 and 16 is piv-
otally connected with one of the posts 13 on pivot
pins 17 and 18 which engage through openings in
the flattened upper ends 19 thereof with the rear
ends of the link members 15 disposed on one side
of the flattened upper ends 19 of the posts respec-
tively and with the rear ends of the link members
16 disposed on the other side thereof.

The link members 15 and 16 of each pair are
pivoted at their forward ends to the leg 20 of an
angle bracket 21 on pivot pins 22 and 23 respec-
tively with the forward ends of the link members
15 being disposed on one side of said legs respec-
tively and with the forward ends of the links 16
being disposed on the other side of the said legs.
The legs 20 are disposed in alignment with the
flattened upper ends 19 of the posts 13. The
angle brackets 21 each include a leg 24 disposed
at right angles with the leg 20 thereof and to
which the panel 10 is secured by screws or equiv-
alent fastening means extending through open-
ings in the legs 24. The legs 20 are provided with
lugs 25 which are adapted to be engaged by the
link members 16 to limit the swinging movement
of the links and to dispose the panel 10 in the
angular relation shown in Figs. 2 and 4 of the
drawings. The posts 13 are also provided with
outwardly projecting lugs 26 which are disposed
in the path of movement of the link members 16
respectively and which form stops for limiting

2

the upward swinging movement of the link members to dispose the back rest in the out-of-the-way position shown in Fig. 7 of the drawings. The pivot pins 17 and 22 in the pairs of link members are formed with enlarged heads and the link members 16 and 15 are respectively provided with recesses 28 and 29 into which the heads are adapted to snap when the angle brackets 21 and panel 10 are moved to the out-of-the-way position above the posts 13 as shown in Fig. 7 of the drawings. The link members 15 and 16 of each pair are disposed in crossed formation when the panel 10 is arranged in operative position to constitute a support for the back of an individual disposed in seated position on the couch, and when the couch is to be used as a bed, as illustrated in Fig. 3 of the drawings, the back rest is swung to a position above the posts 13 with the link members arranged in substantially parallel relation and the panel reversed and disposed with the forward face located rearwardly.

In the form of the invention illustrated in Figs. 8 to 10 inclusive of the drawings, the back rest includes a panel 35 extending longitudinally of a couch 36 and which is affixed thereto so as to provide a back rest for an individual seated on the couch. In this form of the invention the panel 35 is affixed to an upholstered back 37 having stuffed or resilient forward cushion 39. The panel 35 is affixed to the back 37 below the transverse center thereof so as to permit of rocking of the upholstered back to different angular positions as shown in Fig. 8 of the drawings by pressure of the occupant thereagainst.

The panel 35 is mounted on vertical posts 41 located adjacent the ends of the couch which posts are secured thereto by rivets 42 or equivalent fastening means with the upper ends of the posts projecting above the couch and connected with the panel 35 by pairs of flat link members 43 and 44 similar to the link members 15 and 16 in the previous form of the invention. The link members 43 and 44 of each pair are pivotally connected with a flattened upper end 45 of one of the posts on pivot pins 46 and 47 with the forward ends of the link members of each pair being pivoted to a leg 49 of an angle bracket 50 on pivot pins 51 and 52 respectively.

The link members 43 and 44 of each pair are disposed in crossed formation, similar to the previous form of the invention, when the panel 35 is arranged in operative position to constitute a support for the back of an individual disposed in seated position on the couch and when the couch is to be used as a bed, as illustrated in Fig. 9 of the drawings, the back rest is swung to a position rearwardly of the posts 41 to dispose the link members in substantially parallel upwardly extending relation and the panel reversed and arranged with the forward face thereof located rearwardly. For this purpose the link members 43 and 44 of each pair are pivoted to the posts 41 to dispose the pivoted ends of the link members 43 on one side of the flattened upper ends 45 of said posts respectively and with the pivoted ends of the link members 44 disposed on the other side thereof. The forward ends of the link members 43 are disposed on one side of the legs 49 of the angle brackets 50 while the forward ends of the link members 44 are pivotally connected with said legs on the opposite sides thereof.

Each of the angle brackets 50 also include a leg 53 which is disposed at right angles to the leg 49 thereof and to which the panel 35 is secured by screws or equivalent fastening means.

The said legs 49 are provided with lugs 54 which are adapted to be engaged by the link members 44 to limit the swinging movement of the link members and to dispose the panel 35 in the angular relation shown in Figs. 8 and 10 of the drawings. The posts 41 are also provided with outwardly projecting lugs 55 which are disposed in the path of movement of the link members 44 respectively and which form stops for limiting the upward swinging movement of the link members to dispose the back rest in the out-of-the-way position shown in Fig. 9 of the drawings. The pivot pins 46 and 52 are formed with enlarged heads and the link members 43 and 44 are respectively provided with recesses 56 and 57 into which the heads are adapted to snap when the angle brackets 50 are moved to the out-of-the-way position shown in Fig. 9 of the drawings to thereby lock the link members 43 and 44 in upwardly projecting relation.

The couches illustrated in the drawings may be of any preferred type such as studio couches which are adapted to be used to form a comfortable seat and to be made up into a bed. While two forms of the invention have been set forth herein, it is to be understood that the same is intended to cover all changes and modifications of the forms herein illustrated for the purposes of the disclosure, which do not constitute departures from the spirit and scope of the invention.

What is claimed is:

1. In a couch of the type adapted to be made into a bed, a couch body, a back rest extending longitudinally thereof, uprights affixed to the couch in spaced apart relation at the rear thereof and projecting above the couch, angle brackets affixed to said back rest, pairs of crossed link members pivotally connected to said uprights respectively and pivotally connected to said brackets for swinging movement of said back rest from a position arranged in superposed relation over the couch with the link members disposed in crossed relation to an out-of-the-way position with the back rest disposed in inverted relation and facing rearwardly and with the link members of each pair disposed in parallel alignment, said angle brackets and said uprights having lugs against which certain of said link members engage for limiting the forward and rearward movements of said back rest, the upper pivotal connections of the link members with the brackets and uprights having enlarged outer ends, and said link members having recessed portions located substantially medially thereof adapted to engage over said enlarged ends of the pivotal connections for latching the link members of each pair in alignment when the back rest is swung to said out-of-the-way position.

2. In a couch of the type adapted to be made into a bed, a couch body having upwardly directed means at the rear thereof, a back rest extending longitudinally of said couch body, brackets affixed to said back rest, pairs of crossed link members adjacent the opposite ends of the couch body pivotally connected to said upright means and pivotally connected to said brackets for swinging movement of said back rest from a position arranged in superposed relation with reference to the couch with the link members disposed in crossed relation to an out-of-the-way position with the back rest disposed in inverted relation and with the link members of each pair disposed in parallel alignment, means carried by said brackets and said upright means against

which certain of said link members engage for limiting the forward and rearward movements of said back rest, and said link members having recessed portions adapted to engage over enlarged projections on said brackets and upright means for latching the link members of each pair in alignment when the back rest is swung to said out-of-the-way position.

JAMES PILIERO.
